UNITED STATES PATENT OFFICE

146,260

DESIGN FOR A GREASE PUMP

Homer A. Lange, Cincinnati, Ohio, assignor to Balcrank, Inc., Cincinnati, Ohio, a corporation of Ohio

Application November 28, 1945, Serial No. 124,149

Term of patent 3½ years

(Cl. D46—1)

To all whom it may concern:

Be it known that I, Homer A. Lange, a citizen of the United States, residing at Cincinnati, in the county of Hamilton and State of Ohio, have invented a new, original, and ornamental Design for a Grease Pump, of which the following is a specification, reference being had to the accompanying drawing, forming a part thereof.

The figure is a perspective view of a grease pump showing my new design.

The side of the pump not shown is substantially like the side shown in the drawing.

I claim:

The ornamental design for a grease pump, substantially as shown and described.

HOMER A. LANGE.
